Filed July 7, 1965, Ser. No. 470,294
 15 Claims. (Cl. 89—14)

The present invention relates to a recoil booster for blank cartridge firing or maneuver practice of heavy or very heavy machine guns adapted to recoil in their supports in the mounts thereof.

A recoil booster is already known for machine guns of this type in which a gas collector sleeve having a throttle nozzle is inserted into the propellant charge gas stream. In connection therewith, it has also been proposed already to reduce the masses to be moved during recoil by a subdivision of the barrel into a barrel rear section and a barrel forward section, whereby the gas-collecting sleeve with the throttle nozzle is then accommodated at the rear end of the barrel front section and the latter is displaceably mounted over the barrel rear section. Upon firing, the barrel rear section is thereby thrown backwards for actuation of the automatic gun mechanism by the gas surge dammed up by means of the throttle nozzle within the gas-collecting sleeve. In order that harmful gas shocks and impacts do not occur thereby, the barrel front section, together with the gas-collecting sleeve secured thereon is moveable in the forward direction. In order to avoid with this movement caused by the gas pressure built-up within the gas-collecting sleeve behind the throttle nozzle that the barrel front section strikes with the rear end flange of the gas-collecting sleeve hard against the counter abutment collar formed rigidly at the barrel rear section, a spring is inserted between the barrel rear section and the barrel front section which dampens both the forward movement of the barrel front section as well as the rearward movement of the barrel rear section.

Such a spring, however, is not only strongly loaded and stressed but is also subjected in the course of its length of life to certain changes by fatigue appearances, etc., whence the operating efficiency has to be carefully supervised at all times which is both complicated and expensive. The present invention is concerned with the task of avoiding the use of such a spring yet maintaining the damping of the movements caused by the built-up gas pressure in the gas-collecting sleeve and to assure the damping action in a completely satisfactory manner.

With a recoil booster having a gas-collecting sleeve provided with a throttling nozzle for blank cartridge test firing or maneuver practice of heavy or very heavy machine guns supported in the mount thereof for recoil movement, whose maneuver barrel is subdivided into a barrel front section provided at its rear end with the gas-collecting sleeve and into a barrel rear section displaceably inserted with its front end into the gas-collecting sleeve, the purposes of the present invention are achieved in that a pre-throttling nozzle is arranged in the forward end of the bore of the barrel rear section.

As compared to an arrangement without a pre-throttling nozzle, the inflow of the propellant gases into the space of the gas-collecting sleeve is slowed down by the measure according to the present invention so that there takes place within the gas-collecting sleeve a slower build-up of the pressure effecting by its action on the front end face of the barrel rear section the recoil movement thereof and correspondingly a softer recoil impulse is imparted to the barrel rear section which obviates the arrangement of a spring and its attendant considerable uncertainties for the damping of the recoil movements.

It is known, per se, with recoil boosters for machine

guns to operate with two throttling places one disposed behind the other. However, such prior art arrangements are not concerned with recoil boosters for heavy or very heavy machine guns having a subdivided barrel but only are concerned with such recoil boosters as are used with machine guns of normal caliber. Therebeyond, it is not intended with these known recoil boosters to dampen the recoil of sliding masses in a safe and completely effective manner.

10 Accordingly, it is an object of the present invention to provide a recoil booster for heavy and very heavy automatic guns which obviates by simple means, the aforementioned shortcomings and drawbacks encountered with the prior art constructions.

15 It is another object of the present invention to provide a recoil booster which obviates the need of any damping springs, yet effectively and reliably dampens the movements of the subdivided barrel sections in such a manner that no hard and sudden impacts occur between these parts.

20 A further object of the present invention resides in the provision of a recoil booster for very heavy machine guns which assures reliable operation thereof by safely and effectively damping the recoil of the sliding masses, 25 yet avoids complicated mechanical parts that are subject to changes in the performance characteristics during normal operation.

25 Still another object of the present invention resides in the provision of a recoil booster for heavy and very heavy machine guns which prevents shocks and impacts in the guns as a result of recoil movements.

30 These and other objects, features, and advantages of the present invention will become more obvious from the following description when taken in connection with the 35 accompanying drawing which shows, for purposes of illustration only, one embodiment in accordance with the present invention, and wherein:

35 FIGURE 1 is a longitudinal cross-sectional view through the recoil booster in accordance with the present invention with the parts thereof in the position occupied during firing; and

40 FIGURE 2 is a longitudinal cross-sectional view of the recoil booster similar to FIGURE 1, showing the various parts thereof in the normal rest position.

45 Referring now to the drawing wherein like reference numerals are used throughout the two views to designate like parts, reference numeral 10 designates therein the barrel front section and reference numeral 12 the barrel rear section of the subdivided gun barrel. The bore of the barrel front section 10 is enlarged at the rear end so that the thus-obtained enlarged bore 13 forms a gas-collecting sleeve G. The barrel front section 12 is slidably mounted by means of this enlarged gas-collecting sleeve G on the forward end 14 of the barrel rear section 12 55 which is machined to proper dimensions for that purpose. An external thread is provided along the outer surface of the gas-collecting sleeve G for purposes of the threaded connection of a clamping or retaining nut 23 which, in turn, is again provided rearwardly along its outer surface with an external thread 15 for the threaded connection with a clamping or retaining counter nut 24.

60 The fixed barrel casing of the gun is designated by reference numeral 18 which is provided at the forward end with an external or outwardly directed flange 18'. The retaining nut 23 extends over the external flange 18' of the barrel casing 18. Two half-annular segments of a divided or split spacer ring 25 abut rearwardly against the external flange 18' of the barrel casing 18; the spacer ring 25 takes over by means of the retaining counter 65 nut 24 the fixing and securing of the retaining nut 23 and therewith of the barrel front part 10 inclusive the gas-collecting sleeve G at the barrel casing 18.

The interior space of the gas-collecting sleeve G is in communication at the front thereof with the bore of the barrel front section 10 by means of a throttling nozzle 16 and a pre-throttling nozzle 17 is disposed forwardly in the bore of the barrel rear section 12. A gas-discharge channel 19 extends radially through the casing of the retaining nut 23 which channel has an extension toward the interior 13 of the gas-collecting sleeve G.

The recoil booster in the presence of only one throttling nozzle would operate as follows:

If a plastic blank cartridge is fired, then the recoil booster is in the position of "forward movement." The propellant charge gas stream leaves the cartridge case and enters into the bore of the barrel rear section 12, is dammed up in the gas-collecting sleeve G, and exerts thereby a rearwardly directed impulse on the front face of the barrel rear section 12 so that the latter receives a sufficient recoil movement which suffices for the actuation of the automatic mechanism of the gun. This recoil impulse takes place by reason of the sudden damming up of the gas in an impact-like manner which results in shocks and vibrations of the gun.

If now the pre-throttling nozzle 17 is installed into the recoil booster according to the present invention ahead of the throttling nozzle 16, then the gas surge is throttled before it exerts an impulse on the front face of the barrel rear section 12. The gas surge expands within the gas-collecting sleeve G so that the impulse becomes softer, yet lasts for sufficient length of time until the complete recoil of the barrel rear section 12 is terminated. The length of the recoil impulse is maintained by the throttle nozzle 16 in front of the gas-collecting sleeve G. When the complete recoil of the barrel rear section 12 is reached, then the forward end of the recoiling barrel rear section 12 opens up the lateral gas discharge channel 19 and the remaining gases escape in part through the channel 19 into the atmosphere and in part through the throttle nozzle 16 into the bore of the barrel front section 10. Also, this discharge may be lengthened if one exchanges the throttle nozzle 16 with one having a smaller nozzle diameter. The cadence of the gun is thereby decreased.

While I have shown and described one embodiment in accordance with the present invention, it is understood that the same is not limited thereto but is susceptible of numerous changes and modifications as known to a person skilled in the art; and I therefore do not wish to be limited to the details shown and described herein but intend to cover all such changes and modifications as are encompassed by the scope of the appended claims.

I claim:

1. A recoil booster for blank-cartridge practice firing of recoiling heavy and very heavy machine guns, comprising:

barrel means subdivided into a front barrel section and into a rear barrel section separate from said front barrel section,
throttling nozzle means mounted at the rear end of the bore of the front barrel section,
and pre-throttling nozzle means arranged at the front end of the rear barrel section.

2. A recoil booster for blank-cartridge practice firing of recoiling heavy and very heavy machine guns, comprising:

barrel means subdivided into a front barrel section and into a rear barrel section separate from said front barrel section,
said front barrel section being provided at the rear end thereof with chamber means forming a gas-collecting chamber,
said front barrel section being slidably mounted with said chamber means over the front end of the rear barrel section,
throttling nozzle means mounted at the rear end of the bore of the front barrel section,

and pre-throttling nozzle means arranged at the front end of the rear barrel section.

3. A recoil booster for blank-cartridge practice firing of recoiling heavy and very heavy machine guns, comprising:

barrel means subdivided into a front barrel section and into a rear barrel section separate from said front barrel section,
said front barrel section being provided at the rear end thereof with chamber means forming a gas-collecting chamber,
said front barrel section being slidably mounted with said chamber means over the front end of the rear barrel section,
throttling nozzle means mounted at the rear end of the bore of the front barrel section,
pre-throttling nozzle means arranged at the front end of the rear barrel section,
and means for controlling the length of recoil movement of said rear barrel section including discharge means in the walls forming said chamber means which are valved by said barrel front section.

4. A recoil booster for blank-cartridge practice firing of recoiling heavy and very heavy machine guns, comprising:

a relatively fixed gun casing,
barrel means subdivided into a front barrel section and into a rear barrel section separate from said front barrel section,
said front barrel section being provided at the rear end thereof with an enlargement forming a gas-collecting chamber,
said front barrel section being slidably mounted with said enlargement over the front end of the rear barrel section,
throttling nozzle means mounted at the rear end of the bore of the front barrel section,
pre-throttling nozzle means arranged at the front end of the rear barrel section,
and means threadably connecting said barrel front section with said casing.

5. A recoil booster for blank-cartridge practice firing of recoiling heavy and very heavy machine guns, comprising:

a relatively fixed gun casing having an outwardly directed flange,
barrel means subdivided into a front barrel section and into a rear barrel section separate from said front barrel section,
said front barrel section being provided at the rear end thereof with an enlargement forming a gas-collecting chamber,
said front barrel section being slidably mounted with said enlargement over the front end of the rear barrel section,
throttling nozzle means mounted at the rear end of the bore of the front barrel section,
pre-throttling nozzle means arranged at the front end of the rear barrel section,
and means threadably connecting said barrel front section with said casing including a nut threadably secured over the rear end of said barrel front section, a counter nut threadably secured to said first-mentioned nut, and spacer means between said flange and said counter nut.

6. A recoil booster for blank-cartridge practice firing of recoiling heavy and very heavy machine guns, comprising:

a relatively fixed gun casing,
barrel means subdivided into a front barrel section and into a rear barrel section separate from said front barrel section,
said front barrel section being provided at the rear end thereof with an enlargement forming a gas-collecting chamber,

said front barrel section being slidably mounted with said enlargement over the front end of the rear barrel section,
 throttling nozzle means mounted at the rear end of the bore of the front barrel section,
 pre-throttling nozzle means arranged at the front end of the rear barrel section,
 means for controlling the stroke of recoil movement of said barrel rear section,
 and means threadably connecting said barrel front section with said casing.

7. A recoil booster for blank cartridge practice firing of recoiling heavy and very heavy machine guns, comprising:

a relatively fixed gun casing having an outwardly directed flange,
 barrel means subdivided into a front barrel section and into a rear barrel section separate from said front barrel section,
 said front barrel section being provided at the rear end thereof with an enlargement forming a gas-collecting chamber,
 said front barrel section being slidably mounted with said enlargement over the front end of the rear barrel section,
 throttling nozzle means mounted at the rear end of the bore of the front barrel section,
 pre-throttling nozzle means arranged at the front end of the rear barrel section,
 and means threadably connecting said barrel front section with said casing including a nut threadably secured over the rear end of said barrel front section, a counter nut threadably secured to said first-mentioned nut, and spacer means between said flange and said counter nut, means for controlling the stroke of recoil movement of said barrel rear section including discharge aperture means in said nut and in the portion of said chamber wall which is valved by said barrel front section.

8. A recoil booster for a weapon having automatic recoil elements comprising:

a barrel having a bore;
 said barrel including a front section having a first portion of said bore and an aligned separate rear section having a second portion of said bore;
 first throttling nozzle means in said first bore portion; separate second throttling nozzle means in said second bore portion;
 means for mounting said front and rear barrel sections for relative movement generally parallel to said bore between a normal position and a recoil position;
 gas collecting chamber means in fluid communication with said bore downstream of said second throttling means and upstream of said first throttling means, relative to the travel of combustion gasses in said bore from said rear section to said front section, for driving said front and rear sections relative to each other from said normal position to said recoil position with a force correlated with the gas pressure within said chamber means to actuate the automatic recoil elements during firing of the weapon.

9. The device of claim 8, wherein said first throttling nozzle means is in the rearmost portion of said first bore portion and said second throttling nozzle means is in the forwardmost portion of said second bore portion.

10. The device of claim 9, wherein said chamber means

is formed by and said mounting means includes one of said barrel sections having a hollow outwardly opening tubular steering portion adjacent to and telescopically receiving the adjacent end of the other of said barrel sections, said sleeve portion having an internal diameter greater than and an extension of the bore portion in said one of said barrel sections to constitute said sleeve portion a working chamber and said adjacent end of the other of said barrel sections a piston.

10. The device of claim 10, including gas discharge channel means in said sleeve portion for venting the gasses from said chamber means only after said sections have moved a substantial distance from said normal position to said recoil position, and for being closed by said piston in said normal position and opened in said recoil position.

11. The device of claim 11, wherein said sleeve portion is on said front barrel section and has a threaded portion on its exterior; a nut-threaded onto said sleeve portion and having a rearwardly opening externally threaded tubular portion; a fixed barrel casing surrounding said rear barrel section, telescoped at its forward end into said nut tubular portion and having a radially outwardly extending flange means; an additional nut threaded onto said first mentioned nut and having a radially inwardly extending flange means rearward and radially inwardly of said first mentioned flange means for rigidly mounting said barrel casing to said rear barrel section.

12. The device of claim 13, wherein said chamber means is formed by and said mounting means includes one of said barrel sections having a hollow outwardly opening tubular sleeve portion adjacent to and telescopically receiving the adjacent end of the other of said barrel sections, said sleeve portion having an internal diameter greater than and an extension of the bore portion in said one of said barrel sections to constitute said sleeve portion a working chamber and said adjacent end of the other of said barrel sections a piston.

13. The device of claim 13, including a gas discharge channel means in said sleeve portion for venting the gasses from said chamber means only after said sections have moved a substantial distance from said normal position to said recoil position, and for being closed by said piston in said normal position and opened in said recoil position.

14. The device of claim 8, including means for removably mounting each of said throttling nozzle means for replacement to change the gas pressure within said chamber means during firing and the resulting recoil characteristics.
